CLAIM

The ornamental design for a display device, as shown and described.

DESCRIPTION

FIG. 1 is a perspective view of a display device according to the present design, shown in an unfolded state;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the display device shown in an alternate configuration with one side folded towards the front;

FIG. 9 is a perspective view of the display device shown in an alternate configuration with another side further folded towards the rear;

FIG. 10 is a perspective view of the display device shown in an alternate configuration with one side folded towards the front, and another side bent towards the rear; and,

FIG. 11 is a perspective view of the display device shown in an alternate configuration with one side unfolded and another side bent towards the rear.

In the drawings, the broken lines illustrate portions of the display device that form no part of the claimed design.
